ALFRED N. GOLDSMITH AND IRVING WOLFF, OF NEW YORK, N. Y., ASSIGNEES TO
RADIO CORPORATION OF AMERICA, A CORPORATION OF DELAWARE

SOUND REPRODUCER

Application filed November 5, 1928. Serial No. 317,149.

This invention relates to sound reproducers such as loudspeakers, which are adapted to reproduce sound waves without employing an electrically or mechanically vibrated diaphragm, or which, if desired, will reproduce sound waves by pressure changes without the use of a diaphragm. More particularly this invention relates to sound reproducers in which means are provided for obtaining a modulated high frequency sound wave and in which additional means are provided for detecting the modulated high frequency sound wave to obtain audible frequency pulsations corresponding to its modulations.

It has been suggested that sound could be reproduced by modulating a source of high or inaudible frequency pulsations to obtain a modulated high frequency sound wave and by radiating this wave into the open air. Such an arrangement, however, will not operate due to the fact that the human ear is not sensitive to high or inaudible frequency sound waves even though the sound waves are modulated at an audible frequency. We propose to overcome this inoperativeness by employing what may be termed an "acoustic detector". The function of such a device is to detect the modulated high frequency sound waves and to radiate into the open air an audible frequency sound wave corresponding to the modulation or envelope of the modulated wave. The modulated high frequency sound wave can be likened to the modulated high frequency carrier wave of radio telephony and it can be detected in the same manner as a modulated high frequency carrier wave to provide an audible frequency wave.

It is an object of this invention to provide a sound reproducer consisting of means for producing a modulated high frequency sound wave and means for detecting the sound wave to obtain an audible frequency wave.

A further object of this invention is to

provide an acoustic detector for our sound reproducer which will be relatively simple in construction and operation and which will detect the high frequency pulsations without distorting the wave form.

Other objects of our invention will become apparent upon reading the following description of a proposed form of the invention in connection with the accompanying drawing illustrating the same.

In the accompanying drawing which discloses a preferred form of the invention and a modification thereof:

Figure 1 is a diagrammatic illustration of the complete sound reproducer;

Figure 2 is a plan view showing the details of the acoustic detector employed in Figure 1;

Figure 3 is an end view of the acoustic detector illustrated in Figure 2;

Figure 4 is a section on line 4-4 of Figure 2;

Figure 5 is a plan view of a modified form of the acoustic detector;

Figure 6 is an end view of the modification illustrated in Figure 5;

Figure 7 is a section on line 7-7 of Figure 5; and

Figure 8 is a diagrammatic representation of a Venturi tube on which the theory of the operation of our acoustic detector is based.

Referring more particularly to the drawing 11 represents a radio receiver or a microphone or any similar source of energy for modulating the constant amplitude high frequency sound waves set up by the apparatus diagrammatically illustrated at 12. The source of high frequency sound waves illustrated by reference character 12 may be a mechanically vibrated member, an electrically vibrated crystal, a Corona discharge member, or any other means for creating high frequency pulsations consisting of condensations and rarefactions. The modulating current from the member 11 may be at

a radio frequency such as the modulated carrier wave used in radio telephony, or it may be at an audio frequency such as a detected carrier wave. The modulating current may 5 be applied directly to the source at 12 or it may mechanically or electrically modulate a beam of constant amplitude high frequency pulsations set up by the source.

For example, the means for causing the 10 modulated super-audible sound vibrations may consist of a small member which is mechanically vibrated by means of an alternating current field such as is described in the third addition No. 20,804 to French Patent No. 488,190. The means may also consist of a crystal which is vibrated at a modulated super-audible frequency by applying modulated radio frequency currents thereto. The modulated high frequency energy may 15 also be obtained from a Corona discharge which is energized with modulated radio frequency energy or it may be obtained from a talking arc energized in the same manner as shown by the patent to Bothe No. 1,567,230.

20 The beam of modulated high frequency pulsations is indicated at 13 and the acoustic detector for rendering the high frequency pulsations audible, is indicated at 14. The energy from the source 12 due to its high 25 frequency and short wave length, can be radiated in the form of a beam that is adapted to be directed in any desired direction. This beam of energy is directed toward the detector 14 which may be located adjacent the source 12 or which may be positioned some distance from the source. In the latter case the decrease in the energy received by the detector is hardly noticeable due to the fact that the energy can be transmitted 30 in a beam without diffusing or greatly decreasing in strength.

Various types of acoustic detectors can be employed for obtaining an audible frequency wave from the modulated inaudible 45 frequency wave just as various circuits can be used for detecting modulated carrier waves in radio telephony. An approved form of an acoustic detector is illustrated in Figures 2, 3 and 4 and a modified form is 50 illustrated in Figures 5, 6 and 7. Referring to the device illustrated by Figures 2, 3 and 4, the detector consists of a member 15 forming a plurality of sound wave openings or 55 passage-ways 16 which are provided with constrictions 17, in a manner similar to a Venturi tube. The constricted portions 17 of the sound wave openings or passage-ways 16 are connected by vents 18 with the atmosphere. 60 The pulsations from which the audible frequency sound wave is obtained are set up in these vents 18 by the pressure variations taking place in these vents as the result of the velocity variations of the air particles 65 which are given motion by the sound waves passing through the passage-ways 16.

In order for the modulated high frequency sound wave to retain its identity and not be destroyed by interference it is advisable that the radial dimensions of the passage-ways be limited to a value not much larger than the 70 wave length being transmitted. As the high frequency energy has a relatively short wave length it is usually necessary to employ a plurality of openings or passage-ways 16 arranged alongside of each other in order to 75 obtain sufficient energy for the reproduction of the sound.

The modification illustrated by Figures 5, 6 and 7, operates in the same manner as the detector illustrated by Figures 2, 3 and 4. 80 In this modification, however, a diaphragm member 19 is provided and the vent 18 is modified to form an opening 20 which will function to collect and amplify the sound waves from the diaphragm 19 in the same 85 manner as the horn of an ordinary loud-speaker.

The diaphragm is made of any suitable material either metallic or non-metallic in 90 nature and it may be clamped at its edges or suspended by suitable flexible suspending means. A preferable method is to suspend the diaphragm by means of a strip of velvet fastened between the edge of the diaphragm and the supporting member. By making the 95 restoring force of the suspending means sufficiently low, the natural period of the vibrating system is obtained at a frequency below the audible frequency range.

The diaphragm 19 forms with the member 15, the constricted opening or passage-way 16. The diaphragm is positioned at the constricted portion 17 so that it can be affected by the pressure changes resulting from the 100 Venturi effect.

It is usually preferable to construct the acoustic detector 14 from a material whose natural period of vibration does not lie within the audible frequency range.

In explaining the theory of operation of our acoustic detector reference is had to the Venturi tube diagrammatically represented by Figure 8. In a Venturi tube the pressure at the constricted portion, indicated at B in Figure 8, is not a linear function of the velocity or displacement of air particles at that point, but contains a term which is a function of the square of the velocity or displacement of these particles. The pressure is represented by the equation $p = mv + nv^2$, (see Raleigh's Theory on Sound, volume 2, page 13, 1926 Edition) where m and n are constants and v is the velocity of the air particles. Strictly speaking, this equation is true for any sound wave but ordinarily the constant n is so small that its term is negligible compared with the m term. However, when the sound wave passage-way is constricted as in a Venturi tube, the velocity becomes sufficiently large so that when v is squared the 110

term nv^2 produces a pressure which will affect the human ear. As the pressure is sufficiently great to affect the human ear and as the pressure depends upon the square of the velocity, the ear will be able to respond to the envelope of the pressure impulses. This theory may be compared with the theory of detection by means of vacuum tubes.

In other words as a sound wave, or a wave corresponding to a sound wave but having a frequency above audibility, moves through the air it sets the air particles in motion. The air particles move forward and backward through a path forming a closed cycle. The forward motion takes place, say, with the condensation impulse and the rearward motion with the following rarefaction impulse. The velocity of motion and the length of the path or the duration of the motion, depend upon the frequency and amplitude of the sound wave. Thus, at A and B the air particles will be moving forward and backward at velocities proportional to the pressure and rarefaction impulses of the sound wave and having a definite relation to each other. The ratio between the velocity at A and the velocity at B being approximately inversely proportional to the respective areas.

Referring again to Figure 8, as the pressure at D varies proportionally to $mv + nv^2$ the direction of motion of the air particles can be disregarded. That is, the pressure variation at D has a part which is the same, provided the velocity is the same, regardless of whether the direction of motion is from A to C or from C to A. This, in effect, is the same as if the impulses at B were all in the same direction, that is, as if the condensation impulses and rarefaction impulses were rectified so as to consist wholly of condensation impulses or rarefaction impulses. As these impulses contain the same modulation or envelope as the original beam of high frequency energy, the ear drum can respond to the envelope of the impulses just as the telephone diaphragm can respond to the envelope of the detected carrier wave pulsations. Thus, an audible frequency sound wave is obtained at D.

The sound waves from the vents 18 or from the diaphragm 19 may be collected in amplifying horns or directed to some particular point as desired. This is not necessary, however, as the sound waves emanating from these vents usually have sufficient amplitude so that amplifying horns are not required.

In the appended claims the term "constricted passageway" is intended to describe a passageway having a constricted portion.

While we have illustrated only two types of acoustic detectors it is to be understood that various other devices may be employed for the detection of modulating high frequency sound waves and we do not desire to be limited by the arrangement shown but

only by the scope of the appended claims.

We claim:

1. An acoustic system comprising a source of modulated super-audible frequency sound waves and an acoustic detector for obtaining an audible frequency sound wave therefrom. 70

2. An acoustic system comprising a source of modulated super-audible frequency sound waves, and means for obtaining audible sound waves from said modulated super-audible frequency sound waves. 75

3. An acoustic system comprising means for providing a beam of modulated super-audible frequency sound waves and means positioned to be affected by said beam of sound waves for obtaining an audible frequency sound wave therefrom. 80

4. An acoustic system comprising a device for generating a modulated super-audible frequency sound wave and an acoustic detector for converting said modulated super-audible frequency sound wave into audible sound vibrations. 85

5. An acoustic system comprising means for setting up a super-audible frequency sound wave, means for modulating said super-audible frequency wave, and means for obtaining an audible frequency wave from the modulated super-audible frequency wave. 90

6. An acoustic system comprising means for setting air particles into motion at a modulated super-audible frequency, and means for obtaining an audible sound wave from the motion of said air particles. 95

7. An acoustic system comprising means for providing a beam of modulated high frequency sound waves, and means independent of said first mentioned means and positioned at a distance from said first mentioned means for detecting said beam of high frequency sound waves to obtain an audible frequency sound wave therefrom. 100

8. An acoustic system comprising means for radiating a modulated super-audible frequency sound wave, and a member provided with a constricted passage-way for detecting said sound wave to obtain an audible sound wave therefrom. 110

9. An acoustic device of the type adapted to respond to the envelope of a modulated sound wave comprising a member provided with a constricted passage-way so small that non-linear effects take place in the sound wave. 115

10. An acoustic device of the type adapted to respond to the envelope of a modulated sound wave comprising a member provided with a constricted passage-way so small that non-linear effects take place in the sound wave, and means cooperating with the constricted portion of said passage-way for radiating audible frequency sound pulsations. 120

11. An acoustic device of the type adapted to respond to the envelope of a modulated sound wave comprising a sound wave pas-

- sage-way having a constricted portion so small that non-linear effects take place in the sound-wave and a vent leading from said constricted portion for obtaining audible frequency sound waves therefrom.
12. An acoustic device of the type adapted to respond to the envelope of a modulated sound wave comprising a member provided with a plurality of sound wave passage-ways, each of said passage-ways having a constricted portion so small that non-linear effects take place in the sound wave, and a vent leading from the constricted portion of each of said passage-ways.
13. An acoustic detector comprising a member containing a sound wave passage-way so small that non-linear effects take place in the sound wave, a constricted portion in said passage-way, and a vent leading from said constricted portion, the diameter of said sound wave passage-way being not much larger than the wave length of the sound wave being detected.
14. An acoustic detector comprising a member provided with intersecting passage-ways one of which is constricted to such an extent that velocity variations in opposite directions are converted into pressure variations in a single direction.
15. An acoustic device of the type adapted to respond to the envelope of a modulated sound wave comprising a member provided with intersecting passage-ways, one of which has a constricted portion so small that non-linear effects take place in the sound wave.
16. An acoustic device of the type adapted to respond to the envelope of a modulated sound wave comprising a member provided with a passage-way dimensioned for rendering audible a speech modulated superaudible frequency sound wave.
17. An acoustic device of the type adapted to respond to the envelope of a modulated sound wave comprising a Venturi tube, having a portion so constricted that non-linear effects take place in the sound wave.
18. The method of detecting modulated high frequency sound waves which consists in passing the sound waves through a passageway having the internal form of a Venturi tube.
19. The method of detecting modulated high frequency sound waves which consists in passing said sound waves through a constricted passageway.
20. The method of detecting modulated high frequency sound waves which consists in passing said sound waves through at least one of a plurality of intersecting passageways at least one of which passageways has a constricted portion.
21. The method of detecting modulated high frequency sound waves which consists in passing said sound waves through a passageway having a constricted portion, which constricted portion is in communication with a second passageway.
22. The method of detecting modulated high frequency sound waves which consists in passing said sound waves through a passageway having a constricted portion, the constricted portion being in communication with a second passageway extending substantially at right angles to the direction of the passageway having the constricted portion.
23. The method of detecting modulated high frequency sound waves which consists in passing said sound waves through at least one of two intersecting passageways which are arranged so as to convert velocity variations in opposite directions into pressure variations in a single direction.
24. The method of detecting modulated high frequency sound waves which consists in passing said waves through a passageway having a constricted portion and having a vent in communication with said restricted portion.
25. The method of detecting modulated high frequency sound waves which consists in distorting the sound wave so as to obtain a pressure differential varying in accordance with the modulation of said modulated wave, by passing said modulated wave through a constricted passageway.
26. An acoustic detector comprising a member provided with a constricted passageway and a movable body adjacent the constricted portion of said passageway and operatively associated therewith whereby pressure variations in said constricted portion cause movement of said movable body.
27. An acoustic detector comprising a member provided with intersecting passageways and a movable body interposed at the point of intersection to substantially cut off communications between said passageways whereby pressure variations in one of said passageways will cause movement of said body and thereby produce pressure variations in the other passageway.
28. An acoustic detector comprising a member provided with a constricted passageway, a second passageway in said member terminating adjacent the constricted portion of the first passageway, said second passageway flaring in cross section from its junction with the first passageway.
29. An acoustic detector comprising a member provided with a constricted passageway, a second passageway in said member terminating adjacent the constricted portion of the first passageway, and a movable body arranged at the termination of said second passageway to substantially shut off communication between said second passageway and the constricted passageway.
30. A system for communicating intelligence comprising means providing a source of intelligence in the form of vibrations, a

source of carrier vibrations in the form of
pressure variations adapted to be trans-
mitted through an elastic medium, means
for modulating said carrier vibrations by the
5 first mentioned vibrations, and means hav-
ing a non-linear characteristic for directly
obtaining acoustic vibrations corresponding
to the first mentioned vibrations from the
modulated carrier vibrations.
